UNITED STATES PATENT OFFICE

154,408

DESIGN FOR A DISPOSAL RECEPTACLE

Edward H. McGraw, Cambridge, Mass.

Application January 15, 1947, Serial No. 136,158

Term of patent 3½ years

(Cl. D58—17)

To all whom it may concern:

Be it known that I, Edward H. McGraw, a citizen of the United States, residing at Cambridge, in the county of Middlesex and State of Massachusetts, have invented a new, original, and ornamental Design for a Disposal Receptacle, of which the following is a specification, reference being had to the accompanying drawings, forming part thereof.

In the drawings,

Fig. 1 is a front view of a disposal receptacle, showing my new design;

Fig. 2 is a side view thereof looking to the left of Fig. 1;

Fig. 3 is a plan view of the disposal receptacle; and

Fig. 4 is a perspective view showing the dis-

posal receptacle mounted on the end of a desk indicated by broken lines.

The parts of the drawing shown in broken lines are for illustrative purposes only.

I claim:

The ornamental design for a disposal receptacle, substantially as shown and described.

EDWARD H. McGRAW.
